SIGNAL LAMP

Donald E. Sweet, Anaheim, Calif., assignor to Electronic Engineering Company of California, Santa Ana, Calif., a corporation of California

Filed Jan. 28, 1963, Ser. No. 73,341

Term of patent 14 years

(Cl. D48—24)

FIG. 1 is a front perspective view of a signal lamp, showing my new design;

FIG. 2 is a side perspective view thereof;

FIG. 3 is a rear elevation thereof; and

FIG. 4 is an elevation as seen from the opposite side of FIG. 2.

The dominant features of my design reside in the portions shown in full lines, which portions are characterized by the specific configuration of the battery casing in association with the light member as shown.

I claim:

The ornamental design for a signal lamp, as shown and described.
